UNITED STATES PATENT OFFICE.

JACOB SPIELDOCH, OF ST. LOUIS, MISSOURI.

NETHER GARMENT.

SPECIFICATION forming part of Letters Patent No. 425,914, dated April 15, 1890.

Application filed September 13, 1889. Serial No. 323,811. (No model.)

To all whom it may concern:

Be it known that I, JACOB SPIELDOCH, of the city of St. Louis, in the State of Missouri, have invented a certain new and useful Improvement in Nether Garments, of which the following is a full, clear, and exact description, reference being had to the accompanying drawings, forming part of this specification.

This invention relates to devices by which, 10 while effecting a perfect fit for the crotch of nether garments, the usual cumbrous cross-seam at the summit of the crotch is avoided; and the invention consists in features of novelty hereinafter fully described, and pointed 15 out in the claims.

Figure I is a detail view showing the crotch of a nether garment with the preferred form of my invention for the centering seams of the crotch. Fig. II is a detail view of the 20 crotch ends of the quarters previous to attachment; and Fig. III is a detail view of a modification, showing the tongues both extending from the sections of one leg and quarter seamed to the sections of the other 25 leg of the garment.

Referring to the drawings, 1 represents the front quarter or section of the right leg, and 2 the rear section of the same.

3 represents the front section of the left 30 leg, and 4 the rear section of the same.

5 represents a tongue that projects from and is integral with one of the front quarters or sections of the garment and is secured to the edge of the cut-away 6 of its correspond- 35 ing coattachable front section by the seam 7.

8 represents a tongue that projects from and is integral with one of the rear sections of the garment, and is secured to the edge of the cut-away 9 of its corresponding coattach- 40 able rear section by the seam 10.

11 represents the longitudinal inside seam that runs lengthwise of the crotch and legs of the garment, the front and rear sections of which are united together thereby; and 12 are the transverse seams that usually cross the first-named seam at the apex of the crotch, providing a very cumbrous and inconvenient cross-seam in the said objectionable form. 45

To avoid the objectionable cross-seam in that 50 location at the apex of the crotch, a seamless crotch has been heretofore devised by the insertion of a tongue-piece at said crotch, but

with the twofold objections of a necessarily imperfect fit, (for there can be no adjustment in form in the center of the tongue itself, 55 where it is most needed,) and also the seam passing all around said tongue, besides making said part cumbrous, also binds against and prevents the accommodating shearing that would otherwise be provided by the texture of the cloth, which is in my device in a great measure self-adjusting to the movements of the wearer of the garment in walking, no cross-seam barring the self-accommodating adjustment of the parts in each movement of 60 the wearer as he walks.

To avoid the objectionable features of the cumbrous cross-seam as usually constructed on the one hand and the misfit of the central crotch-tongue, with the disadvantage of its 70 binding surrounding seam on the other, I have devised my tongues, the base of which tongue in each case is respectively integral with one of the quarters or sections of the legs of the garment, and said tongue has a seam attach- 75 ment to the edge of the cut-away of the corresponding front or rear section with which it is united, as the case may be.

I much prefer to cut my tongues as shown in Fig. II and attach them as shown in Fig. 80 I, as that gives the opportunity for an elastic shearing adjustment in the texture of the cloth in both legs of the garment when the wearer is walking, unbound by either the usual cross-seams or the surrounding seams 85 of a tongue; but said tongues may be cut, when desired, with said tongues both integral with the sections of one leg of the garment and both seamed to the corresponding sections of the reverse leg of said garment, as shown in 90 Fig. III. The crotch attachment shown in this modification in Fig. III only partially obviates the objectionable features alluded to in the usual cross-seam on the one hand, and the center tongue which is seamed all 95 around to the sections of the garment on the other, but does not as completely overcome said objectionable features as does my preferred device. (Shown in Figs. I and II.)

I have shown and described in my preferred form, the tongues respectively integral with the front right-leg section of the garment and with the rear left-leg section of the same, and in each instance seamed to the corresponding

section of the reverse leg; but I do not confine myself arbitrarily to said disposition of the tongues, for it is evident that the respective tongues could be as readily cut integral with the front section of the left leg and the rear section of the right leg without departing from the essential features of the invention.

I claim as my invention—

1. A nether garment having the usual longitudinal leg-seam, two leg portions at the crotch, each provided with an integral tongue extending in line with said seam, and the remaining leg portions cut away opposite said tongues, the latter being secured to the edges

of the leg portions where cut away, substantially as described.

2. A nether garment having one portion of one leg at the crotch and one portion of the other leg at the crotch each provided with an integral tongue in line with the longitudinal leg-seam, the remaining leg portions being cut away opposite said tongues, and the latter being secured to the edges of the leg portions where cut away, substantially as described.

JACOB SPIELDOCH.
